United States Patent Office

Des. 211,011
Patented May 14, 1968

211,011

MOVABLE RESIDENCE

Paul H. Jones, 1345 Scottsville Road,
Rochester, N.Y. 14624

Filed Apr. 27, 1967, Ser. No. 6,862

Term of patent 14 years

(Cl. D13—1)

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 14

FIG. 15

FIG. 16

FIG. 17

FIG. 18

FIG. 19

FIG. 20

FIG. 21

FIG. 1 shows a perspective view of a movable residence according to the invention;

FIG. 2 is a front elevation of the movable residence of FIG. 1;

FIG. 3 is a rear elevation of the movable residence of FIG. 1;

FIGS. 4 and 5 are opposite end elevations of the movable residence of FIG. 1;

FIG. 6 is a front elevation of a movable residence according to the invention showing the garage door open and a window in the garage;

FIG. 7 is a rear elevation of the movable residence of FIG. 6;

FIG. 8 is an end elevation of the movable residence of FIG. 6 showing a door in the side of the garage wall;

FIG. 9 is an end elevation of the movable residence of FIG. 6 showing windows in the garage wall;

FIG. 10 is an end elevation of the movable residence of FIG. 1 cut away to show a door leading to the inside of the garage;

FIG. 11 is a front elevation of a movable residence according to the invention having a garage formed of panelled material;

FIG. 12 is a rear elevation of the movable residence of FIG. 11;

FIGS. 13 and 14 are opposite end elevations of the movable residence of FIG. 11;

FIGS. 15 and 16 are respective front and rear elevations of the inventive movable residence having a garage formed of panelled material and with the garage door opening at the opposite end of the garage from the embodiment illustrated in FIG. 11;

FIG. 17 is an end elevation of the movable residence of FIG. 11 showing windows in the garage wall;

FIG. 18 is a front elevation of a movable residence according to the invention with the garage door oriented opposite to the orientation of FIG. 1;

FIG. 19 is a rear elevation of the movable residence of FIG. 18;

FIG. 20 is a front elevation of a movable residence with the garage door oriented as in FIG. 18, and including a window in the garage; and

FIG. 21 is a rear elevation of the movable residence of FIG. 12 having a window in the garage wall.

The dominant features of the design reside in the portions shown in full lines.

I claim:

The ornamental design for a movable residence, substantially as shown and described.
